Wilson McLean

UNITED STATES PATENT OFFICE.

ARTHUR BATES, OF LEICESTER, ENGLAND, ASSIGNOR, BY MESNE ASSIGNMENTS, TO UNITED SHOE MACHINERY CORPORATION, OF PATERSON, NEW JERSEY, A CORPORATION OF NEW JERSEY.

UPPER-SHAPING MACHINE.

1,426,342.

Specification of Letters Patent. Patented Aug. 22, 1922.

Application filed October 4, 1917, Serial No. 194,721. Renewed December 21, 1920. Serial No. 432,304.

To all whom it may concern:

Be it known that I, ARTHUR BATES, a subject of the King of England, residing at Leicester, Leicestershire, England, have invented certain Improvements in Upper-Shaping Machines, of which the following description, in connection with the accompanying drawings, is a specification, like reference characters on the drawings indicating like parts in the several figures.

This invention relates to machines for shaping the uppers of shoes and more particularly to machines especially designed for shaping the marginal portions of shoe uppers into position for attachment to the soles of the shoes.

The invention is herein shown as embodied in a machine for creasing the upper of a shoe and forming the creased portion into a groove in the edge face of a sole. The illustrated machine is particularly applicable for use in the manufacture of shoes having wooden soles, known as clogs, and the invention is herein set forth with special reference to that application of it although it is understood that the invention is not limited to this use but may be employed with advantage in machines for use in the manufacture of shoes of other types including, for example, stitch-down shoes.

An object of this invention is to provide a machine having power operated means for forming a definite crease in advance of the work guide, the crease enabling the work to be more easily and positively fed along the guide. A further object is to provide power-operated means acting upon the shoe at the rearward side of the guide which will contribute toward the satisfactory formation of the upper materials into the crease and enable the same desirable results to be secured whether the work is fed from right to left or from left to right. It is also an object of the invention to provide a novel relative construction and arrangement of the work treating means and supporting means such that the work is sustained for the action of the treating means while permitting movement of the work to feed the work and allowing movement of the work to and fro for repeated operations of the treating means upon a portion of the work.

Another object of the invention is to pro-

vide improved means for affording compensating movement of the crease forming tools to ensure that both tools will enter into engagement with the work despite inevitable slight departures on the part of the operator from correct presentation of the work to the machine in the course of this operation.

A feature of the invention consists in a novel organization comprising a guide and a crease forming tool arranged for actuation relatively to the guide and acting upon the work in line with the guide relatively to the direction of feed of the work, that is, along the path of traverse of the tool and guide along the work.

A further feature of the invention consists in improved means by which the crease forming tool is rendered self accommodating to the direction in a vertical plane of the face of the work treated and preferably the construction is such that the tool is returned to predetermined relation to the guide when displaced by variations of the direction of the face of the work in said vertical plane.

Another feature of the invention consists in a plurality of crease forming tools arranged for movements of accommodation to the inclination of the work relatively to the direction of operation of the crease forming tools and, as herein shown, the tools are interconnected so that elevation of one effects a depression of the other, the construction being preferably such that the movements of the tools are equal and opposite.

In the illustrative machine there is provided a plurality of crease forming tools arranged one each side of the guide, one tool being in advance of the guide and the other at the rear of the guide relatively to the direction of the feed of the work, the tools being preferably connected, as described, so that elevation of one relatively to the guide will produce a corresponding depression of the other relatively to the guide. This construction permits accommodation of the tools to the inclination relatively to a horizontal plane of the face of the work acted upon while the said face is held against the guide.

Another feature of the invention consists in a construction and arrangement of

the tools and the guide whereby there is provision for relative movement of accommodation between the tools and the guide laterally of the direction of the feed of the work. This construction permits the crease forming tools to adapt themselves to variations in the direction of the path of traverse of the tools along the work in a horizontal plane.

10 A further feature of the invention consists in a novel organization comprising means for operating on one of the edge faces of a shoe sole, for instance in the groove of a wooden sole, and means for supporting the 15 edge of the shoe opposite to that being treated by the tool with the sole in a substantially vertical position. As shown, the support has an inclined resting face which enables portions of the shoe of varying width 20 to be supported upon the rest without material variation in the inclination of the shoe sole. Preferably the support is adjustable both to vary the inclination and to vary the distance of the rest from the tool. It is important that the point of support of the shoe, 25 which preferably is the edge corner of the sole adjacent to the tread face and opposite to the operating means, shall remain under the point treated by the crease forming tool, 30 and hence the support is of small lateral extent. This also permits the shoe to be rocked on the rest as a fulcrum in a vertical plane. By rocking the shoe the action of the operating means upon the upper is enhanced and 35 various refractory portions of the upper may be repeatedly treated to the action of the operating means, for instance the crease forming tools, by rocking the shoe upon the rest first in one direction and then in the 40 other.

These and other features of the invention will appear more fully from the following detailed description when read in connection with the accompanying drawings and will be pointed out in the appended claims.

In the drawings,—

Fig. 1 is a side view of a machine embodying this invention; and

Fig. 2 is a front view of the forward portion of the machine.

Referring to the drawings, the numeral 2 indicates the frame of the machine in which are guides 6, 6 for a vertically moving plunger 8. On the plunger 8 is a loose sleeve 10 on the inner side of which is pivoted a link 12 by a pin 14 which extends beyond the link to engage a vertical guide 16 formed in a part 18 clamped at 19 to a hub on the frame 2 through which a shaft 24 extends. The guide 16 prevents rotation of the sleeve 55 10 on the plunger 8 and permits vertical movement thereof. The lower end of the link 12 is mounted on a crank pin 20 eccentrically fixed in a disc 23 on the end of the shaft 24 to which power is applied rapidly 60 65

to reciprocate the plunger 8 in the guides 6, 6. On the plunger 8 above the sleeve 10 is a nut 26 adjustable to determine the normal raised position of the plunger, the nut being surmounted by a check nut, as shown. Abutting against the lower face of the sleeve 10 is a spring 30 the lower end of which rests on a flange 32 of a sleeve 34 loose on the plunger. Levers 36 are pivoted at 38 to the plunger 8 beneath the flange 32, the plunger 8 being suitably flattened to provide bearing faces for the levers. The ends of these levers are pivoted at 40, 42 to the upper ends of shanks 44, 46, respectively, of crease forming tools 48, 50. The lower end of the 80 plunger 8 is bifurcated to receive a lever 52 pivoted to the plunger at 53 and having its ends bifurcated to receive the shanks 44, 46 which are pivoted thereto by pins 54, 56. The lower ends of the shanks 44, 46 approach 85 each other and lie adjacent to a guide 60 located between them and having a rearward extension slotted to receive a cap screw 61 by which it is secured to a stationary portion of the machine. By this construction, 90 the guide is rendered adjustable forwardly and rearwardly of the crease forming tools. The levers 36, 52 constitute a parallel motion between the crease forming tools 48, 50 so that the elevation of one effects a corresponding depression of the other, the tools therefor accommodating themselves to an inclination in a vertical plane of the face of the work treated by them. It will be noted also that the plunger 8 is free to rotate in 95 its guides 6, 6 so that the crease forming tools may move forwardly and rearwardly with respect to the guide 60 and thus accommodate themselves to variations in a horizontal plane of the direction of the groove 100 or angle into which they crease the upper. When the sleeve 10 is reciprocated by the described connection to the shaft 24, the plunger 8 and crease forming tools 48, 50 will be positively raised by contact of the 105 sleeve 10 with the nut 26 and will be moved downwardly through the spring 30 to cause the crease forming tools to deliver a yielding blow upon the material in the crease. The crease forming tools, as shown herein, have 110 a shape adapted to fit the groove in the edge face of the wooden sole of a clog. It is within the invention so to change the shape of the crease forming tools that they will be adapted to operate in the angle between the 115 side of a last and the margin of the sole of a stitch-down shoe. The operating portion of each of the crease forming tools, as shown, comprises a portion 70 formed to enter the crease in the sole of a clog and above the portion 70 is an overhanging portion 72 which not only has a smoothing action upon the upper just above the crease line but also acts to prevent blows of undue force coming 120 upon the material at the bottom of the crease 125 130

such as would, when operating upon certain materials, cut or otherwise injure them.

To sustain the shoe, a support 80 is provided having a flat tread engaging face 81 covered with leather or other material which will provide a somewhat yielding friction surface. The support is arranged below the crease forming tools 48, 50, in such a position that the plane of the sole when the lower edge thereof is in contact with the rest, will be normally perpendicular. The resting surface 81 is narrow in the direction of the feed of the work and therefore permits fulcruming of the shoe for movement of the sole thereon, the operator having therefore full freedom to tip the work in different directions properly to present the guide 60 for the tools 48, 50 to different parts of the work while resting the edge corner only of the sole adjacent to the tread face and opposite to the operating means against the surface 81. The rest 80 extends at an angle to the horizontal of say 60° and forms part of an angle member pivoted to the frame 2. The other arm 84 of the angle member carries a pin 86 to which is rotatably connected one end of the member 88 which has threaded engagement with a stud 90 on the frame. By turning the squared end 92 of the member 88, the angle of the rest may be varied to suit the work being operated upon.

Having thus described my invention, what I claim as new and desire to secure by Letters Patent of the United States is:

1. In a machine of the class described, in combination, a guide, a crease forming tool at one side of the guide and aligned therewith in the direction of feed of the work, and means for operating the tool toward and from the work.

2. In a machine of the class described, the combination of a guide, a crease forming tool arranged in line with the guide relatively to the path of traverse of the tool and guide along the work, power driven means for operating the tool transversely of said path, and means for permitting self-adjustment of the tool and guide to variations in the direction of said path in a vertical plane.

3. In a machine of the class described, the combination of a guide, a crease forming tool arranged in line with the guide relatively to the path of traverse of the tool and guide along the work, and means permitting self-adjustment of the tool and guide to variations of the direction of said path in a vertical plane, means for actuating the tool transversely of said path, and means tending normally to maintain the tool and guide in predetermined relation relatively to each other.

4. In a machine of the class described, the combination of a guide, a plurality of tools arranged one on each side of the guide along the path of traverse of the guide along the

work, and means for actuating the tools transversely to said path to cause said tools to crease the work.

5. In a machine of the class described, the combination of a guide, and a plurality of creasing tools arranged one on each side of the guide along the path of traverse of the guide along the work, said guide and tools being constructed and arranged for relative self-adjustment laterally of the path of traverse of the tools and guide along the work.

6. In a machine of the class described, the combination of a guide, a plurality of creasing tools arranged one on each side of the guide along the path of traverse of the guide along the work, and means for actuating the tools, said tools being interconnected for self-accommodation relatively to the guide to adapt them for operation upon a face of the work held in a position inclined to the horizontal.

7. In a machine of the class described, the combination of a guide, a plurality of creasing tools arranged one on each side of the guide in line with the path of traverse of the guide along the work, and means for actuating the tools, said tools being interconnected for equal and opposite movement relatively to the guide and adapted for operation upon a face of the work held in a position inclined to the horizontal.

8. In a machine of the class described, the combination of a guide, a plurality of creasing tools arranged one on each side of the guide along the path of traverse of the guide along the work, power means for operating the tools toward and from the work, and means for holding the tools normally in predetermined relation to each other.

9. In a machine of the class described, the combination of a guide, a plurality of creasing tools arranged one on each side of the guide in line with the path of traverse of the guide along the work, and an equalizing connection between the tools whereby the elevation of one will effect depression of the other.

10. In a machine of the class described, the combination of a guide, a plurality of creasing tools arranged one on each side of the guide in line with the path of traverse of the guide along the work, and an equalizing connection between the tools whereby the elevation of one will effect corresponding depression of the other.

11. In a machine of the class described, the combination of a plurality of crease forming tools, means for actuating the tools perpendicularly to the surface of the work which they are to treat, and connections between the tools permitting them to move equally and oppositely in the direction of their actuation in response to pressure of the work against them.

12. In a machine of the class described, the combination of a guide, a crease forming tool arranged adjacent to said guide, means for actuating the tool vertically against work held against said guide, and a rest below the guide having an oblique shoe resting surface at a greater angle to the vertical than the plane of the sole to form a rest for the edge of the sole on the opposite side of the shoe from that operated upon by the crease forming tool. 18. In a machine of the class described, a plurality of crease forming tools, means for actuating the tools toward and from the work, and means tending to hold the acting faces of the tools in horizontal alignment and permitting the tools to be forced out of such alignment by reason of inequalities of the work. 65
- 5 work held against said guide, and a rest below the guide having an oblique shoe resting surface at a greater angle to the vertical than the plane of the sole to form a rest for 10 the edge of the sole on the opposite side of the shoe from that operated upon by the crease forming tool. 19. In a machine of the class described, the combination of a guide, a crease forming tool arranged adjacent to said guide, means for actuating the tool in a vertical direction upon work held against said guide, and a rest below the guide to receive and support the lower edge of the work, said guide being of small lateral extent to permit the work 75 to be tipped upon the rest as a fulcrum to cause repeated operation upon a refractory portion of the upper being creased. 70
- 15 13. In a machine of the class described, the combination of a guide, a crease forming tool arranged adjacent to said guide, means for actuating the tool vertically against work held against said guide, a rest below the guide having an oblique shoe resting surface to receive an edge of the work opposite the guide and support the work at said 20 edge, and means for adjusting the obliquity of the rest to accommodate the rest for work of different widths. 20. In a machine for creasing an upper into a groove in the edge face of a sole, a crease forming tool having a portion shaped to enter the groove and having a lateral portion arranged to smooth the upper adjacent to the groove and to engage a wall of the groove to prevent undue force being applied to the material at the bottom of the groove. 85
- 25 14. In a machine of the class described, an upper engaging tool, a rest below said tool having an oblique shoe supporting surface constructed and arranged relatively to said tool to receive an edge of the work opposite to the side of the shoe to be treated by said tool so as to support the shoe at said edge 30 for the action of the tool with its sole angularly disposed with relation to the shoe supporting face of said rest and in substantial alignment with said tool, and means for relatively reciprocating said tool and said rest. 90
- 30 15. In a machine of the class described, in combination, a guide, a crease forming tool arranged adjacent to said guide, and a rest below said guide having an oblique shoe supporting surface to receive and support the 40 edge of the shoe opposite to the edge to be treated by said tool, said tool and said rest being relatively constructed and arranged to locate and position the shoe with its sole angularly disposed with relation to the shoe supporting face of said rest and in substantial alignment with said tool. 95
- 35 16. In a machine of the class described, the combination of a guide, a crease forming tool arranged adjacent to said guide, means for actuating the tool in a vertical direction upon work held against said guide, and a rest below the guide having an oblique shoe resting surface to receive and support an edge of the work opposite to the guide and of 50 small lateral extent permitting tipping in a vertical plane of the shoe held against the rest. 100
- 40 17. In a machine of the class described, a plurality of crease forming tools, means for actuating the tools toward and from the work, and interconnected means between the tools whereby they are self-accommodated to inclinations of the surface of the work in which the crease is formed. 115
- 45 21. In a machine of the class described, means for operating on one of the edge faces of a shoe sole, means for supporting the shoe during operation thereon comprising an inclined member disposed to contact with the opposite edge face of the sole substantially in vertical alignment with the operating means, and means for varying the 100 inclination of said member to accommodate soles of different sizes. 120
- 50 22. In a machine of the class described, means for operating on one side of a shoe having a wooden sole and means for supporting the shoe during operation thereon comprising a member having an inclined surface disposed for engagement with the corner of the sole formed by the junction of the edge face of the sole opposite to the operating means and the tread face of the sole at a point substantially in vertical alignment with the point of operation on the sole. 110
- 55 23. In a machine of the class described, means for operating in a groove formed in a wooden sole and a work support spaced therefrom constructed and positioned relatively to the operating means for engagement with the corner of the sole between the edge face of the sole opposite to the operating means and the tread face of the sole at a point substantially in vertical alignment with the operating means, said work support being further constructed and arranged for fulcruming the shoe for movement of the sole thereon. 125
- 60 24. In a machine of the class described, means for operating on one of the edge

faces of a shoe sole, and means for supporting the shoe during operation thereon constructed and arranged for engagement only with the corner of the sole between the opposite edge face and the tread face of the sole.

25. In a machine of the class described, means for operating on one side of a shoe and means for supporting the shoe during 10 operation thereon constructed and arranged for engagement with the corner only of the shoe sole formed by the junction of the edge face of the sole opposite to the point of op-

eration on the shoe and the tread face of the sole. 15

26. In a machine of the class described, means for operating in a groove formed in a wooden sole, and means for supporting the sole during operation thereon comprising an inclined member disposed for engagement 20 with an edge corner only of the sole opposite from the operating means.

In testimony whereof I have signed my name to this specification.

ARTHUR BATES.
